UNITED STATES PATENT OFFICE

JOHN CARROLL, OF DOVER, OHIO, ASSIGNOR TO THE REEVES MANUFACTURING COMPANY, OF DOVER, OHIO, A CORPORATION OF OHIO

FRAME FOR COATING PAILS AND THE LIKE

Original application filed November 2, 1928, Serial No. 316,754. Divided and this application filed September 21, 1929. Serial No. 394,322.

The invention relates to the coating of pails, buckets and other articles with zinc, tin or other coating materials and more particularly to a frame or holder for carrying a pail and the like through the coating material, and the present application is a division of my copending application for galvanizing machines, Serial No. 316,754, filed November 2, 1928.

10 In the manufacture of galvanized, tinned and other coated buckets, pails and other metal articles, the same are, under present practice, either formed from sheets which have been previously coated with zinc or tin; 15 or the articles are formed of black sheets and then dipped in the molten zinc, tin or other coating material for coating the same.

The cheaper grades of such coated articles are usually formed from sheets which have 20 been previously coated with zinc or tin, for the reason that a thin coating may be obtained by first galvanizing or tinning the sheet in the usual galvanizing or tin pot provided with rolls which engage opposite sides 25 of the sheets and squeeze the surplus metal therefrom.

However, it has been found by experience that, particularly in the use of galvanized or zinc coated sheets, the coating breaks or 30 cracks in forming the articles of the previously coated sheets. Also, it is not possible in so forming the articles to provide sufficient coating at the seams to properly protect the same against rust or corrosion in use.

35 For this reason, it is customary, under present practice, to make the better grade of such articles from black sheets and then dip the formed article into the molten zinc or tin for coating the same. The metal coating thus 40 formed upon the article properly coats the seams of the article and is not subjected to the cracking or breaking common in the forming of the articles from the previously coated sheets.

45 Although it is known that attempts have been made to produce machines for mechanically coating formed pails, buckets and the like and some few patents have been obtained 50 upon such machines, there is no such appara-

tus, to applicant's knowledge, which has ever been capable of commercial use.

Therefore, all such articles, which are first formed of black sheets, or the like, are dipped by hand into the molten zinc or tin in order 55 to coat the same. This hand dipping is not only very slow and expensive but does not permit of a uniform coating of metal being applied throughout the entire surface of the article and usually results in a coating considerably heavier than is necessary, thus materially increasing the cost of the finished coated article.

The object of the present improvement is to provide an apparatus for coating buckets, 60 pails and other receptacles with zinc, tin or other coating material; and for applying a uniform coating of the desired thickness upon the articles; and for properly covering the seams with a substantial coating of the metal. 65

An embodiment of the invention is illustrated in the accompanying drawings, in which

70 Figure 1 is a front elevation of one of the improved frames or holders to which the invention pertains, showing a pail supported thereon;

Fig. 2, a top plan view of the frame with the pail removed;

Fig. 3, a side elevation of the frame showing the pail thereon; and

Fig. 4, a section on an enlarged scale taken substantially on the line 4—4, Fig. 3.

Similar numerals refer to similar parts throughout the drawings.

The improved frames to which the invention pertains are adapted to be suspended from a conveyer or the like arranged to pass the frames, and the pails or other articles carried thereby, through the coating material.

80 Each frame is provided with a substantially vertical rod 10 arranged to be connected at its upper end to the conveyer or the like and supporting the frame at its lower end.

85 The normally horizontal frame is carried at the lower end of the rod 10 and comprises a pair of diverging arms 11 connected at their outer ends as by the bar 12, to the center 90

of which is fixed the rearwardly extending finger 13.

In the crotch of the arm 11 may be provided a lug 14, adapted to support the bottom portion of a pail or bucket indicated at 15, while the upper portion of the pail rests upon the arms 11 which may be provided with the knife edge lugs 16, the finger 13 extending into the open end of the pail and engaging the interior thereof at a point spaced from the top of the pail, as best shown in Figs. 3 and 4.

This finger 13 is preferably provided on its under side with a knife edge 17 for engagement with the interior of the pail, as illustrated in said figures.

In placing the pails in the frames, the seam, indicated at 18, is located at the bottom, as best illustrated in Fig. 4.

The pails are placed on the frames, as above described, and the frames are lowered into the coating material to submerge the pails therein and move therethrough, the movement preferably being laterally of the pails.

As each pail is raised from the coating material, the frame is preferably tilted backward to allow the coating material uniformly over the same and then forward, pouring the excess of coating material from the pail and in this manner giving an extra heavy coating upon the inside of the seam 18.

I claim:

1. In an apparatus for coating pails and the like, a frame adapted to carry a pail and the like, and including a pair of substantially horizontally disposed, diverging arms for supporting the pail in horizontal position and a finger carried by the outer end portions of the arms and adapted to project inside of the pail.

2. In an apparatus for coating pails and the like, a frame adapted to carry a pail and the like, and including a pair of substantially horizontally disposed, diverging arms for supporting the pail in horizontal position and a finger carried by the outer end portions of the arms and adapted to project inside of the pail and having a knife blade lug for contact with the inner surface of the pail.

3. In an apparatus for coating pails and the like, a frame adapted to carry a pail and the like, and including a pair of substantially horizontally disposed, diverging arms for supporting the pail in horizontal position, a crossbar connected to the outer ends of the arms and a finger carried by the crossbar and adapted to project inside of the pail.

4. In an apparatus for coating pails and the like, a frame adapted to carry a pail and the like, and including a pair of substantially horizontally disposed, diverging arms for supporting the pail in horizontal position, a crossbar connected to the outer ends of the arms and a finger carried by the cross-

bar and adapted to project inside of the pail and having a knife blade lug for contact with the inner surface of the pail.

5. In an apparatus for coating pails and the like, a frame adapted to carry a pail and the like, and including a pair of substantially horizontally disposed, diverging arms, a lug at the crotch of the arms for supporting one end of the pail, and knife blade lugs near the outer end portions of the arms for supporting the other end portion of the pail.

6. In an apparatus for coating pails and the like, a frame adapted to carry a pail and the like, and including a pair of substantially horizontally disposed, diverging arms, a lug at the crotch of the arms for supporting one end of the pail, knife blade lugs near the outer end portions of the arms for supporting the other end portion of the pail, and a finger carried by the outer end portions of the arms and adapted to project inside of the pail.

7. In an apparatus for coating pails and the like, a frame adapted to carry a pail and the like, and including a pair of substantially horizontally disposed, diverging arms, a lug at the crotch of the arms for supporting one end of the pail, knife blade lugs near the outer end portions of the arms for supporting the other end portion of the pail, a crossbar connected to the outer ends of the arms, and a finger carried by the crossbar and adapted to project inside of the pail and having a knife blade lug for contact with the inner surface of the pail.

In testimony that I claim the above, I have hereunto subscribed my name.

JOHN CARROLL.
